UNITED STATES PATENT OFFICE

CLEMENT BOOTH, OF CINCINNATI, OHIO, ASSIGNOR TO CINCINNATI GRINDERS INCORPORATED, OF CINCINNATI, OHIO, A CORPORATION OF OHIO

CENTERLESS GRINDING MACHINERY

Application filed April 9, 1928. Serial No. 268,543.

This invention relates to improvements in grinding machinery and has particular reference to a machine of the centerless type adapted for use in the production of concentrically located tapered shanks on twist drills or like members.

One of the principal objects of the present invention is the provision of improved means for properly positioning and guiding the tapered shank portion of a twist drill or like member during the accurate formation of the taper thereon.

A further object of the invention is the provision of a combination of improved mechanisms for joint engagement with a floating work piece to insure the proper concentric production of a second surface thereon as respects a previously formed portion thereof.

20 A further object of the invention is the provision of an improved work holding fixture which will facilitate the introduction of work in the grinding throat of a centerless grinder and the subsequent withdrawal thereof at the completion of the grinding operation.

An additional object of the invention is the provision of an attachment for application to a standard centerless grinder which will facilitate the production of articles therein by the infeed method.

Other objects and advantages of the present invention should be readily apparent by reference to the following specification taken in conjunction with the accompanying drawings forming a part thereof, and it will be understood that I may make any modifications in the specific structural details hereinafter disclosed within the scope of the appended claims without departing from or exceeding the spirit of the invention.

45 Figure 1 is a front view of a centerless grinder embodying the present invention.

Figure 2 is a horizontal sectional view taken as on line 2—2 of Figure 1.

Figure 3 is a similar section at right angles to Figure 2.

50 Figure 4 is a fragmentary view in eleva-

tion of the fixture and associate portions of the machine.

Figure 5 is a transverse section as on line 5—5 of Figure 4.

Figure 6 is a section on line 6—6 of Figure 3 and Figure 7 is a section through the double gimbal bearing as on line 7—7 of Figure 3.

In the drawings the numeral 10 designates the bed of a conventional centerless grinder having the housing 11 for the grinding wheel 12 which is operated at a high or grinding rate of speed in the direction indicated by the arrow on the housing in Figure 1.

55 Mounted on the bed 10 is a slide 13 having movable therewith and thereon relative thereto the regulating wheel unit 14 supporting the regulating wheel 15. This wheel is located in opposition to the grinding wheel and has its inner operative surface moving in the opposite direction from that of the grinding wheel as is also indicated by the arrow. An adjusting screw 16 and pilot wheel 17 inter-engaged with bracket 18 on bed 10 serve to move the slide 13 relative to the grinding wheel or the unit 14 relative to its slide depended upon the inter-clamped relation of the parts in accordance with the usual commercial centerless grinder construction.

60 Secured upon and rising from the slide 13 a work rest bracket 180 having a portion disposed in the throat between grinding and regulating wheels and carrying the work rest blade 19 having an angularly disposed upper surface 20 inclining upwardly in the direction of and in opposition to the direction of movement of the grinding wheel. By reference particularly to Figures 3 and 4 of the drawings it will be noted that the work rest blade in place of being continuous in form is provided with the upstanding lug 21 for engagement with the periphery of the shank 22 of drill barrel 23 which shank is intended to be formed by the present machine to proper accurate diameter and concentric with the previously ground barrel portion thereof.

65 It is further to be noted that this shank

portion 22 is of tapered form to fit the usual tapered chuck or holder and that consequently the throat opening between opposed operative faces of the grinding and regulating wheels is of tapered formation.

It is to be understood that the taper may be equally formed on the faces of the grinding and regulating wheels as has been illustrated or one of these may be disposed parallel with its axis and a double taper formed on the other. In either event, however, the regulating wheel in place of having continuous contact with the work piece is preferably shaped or formed as by the truing device 24 with a projecting circumferential rib 25 corresponding in location to the lug 21 on the work rest blade and designed to cooperate with said lug and with a predetermined portion of the work piece for the final accurate supporting and positioning of the work piece with respect to the grinding wheel.

To cooperate with the parts just described the work rest blade or bracket 180 preferably carries an abutment or stop 26 to limit endwise or axial movement of the work piece into the machine.

The bracket 180 has a forwardly projecting portion 27 which serves as a support for the work holding and controlling fixture. This fixture comprises a bracket member 30 adjustably secured to the portion 27 by T bolts 29 and having an upstanding portion 28 in turn adjustably supporting the block 30. Block 30 inwardly terminates in yoke arms 31 bearing pivot screws 32 engaging ring 33 which in turn has pivot screws 34 at right angles to screws 32 for engagement with the work guiding sleeve 35. It will thus be noted that sleeve 35 is supported by a universal joint or double gimbal bearing permitting of same being swung from a raised loading position as shown in Figure 4 to the operative position of Figure 3 and return and also permitting of lateral play or swinging movement of the sleeve as limited by stop plate 36 adjustably secured to lug 37 and located at the regulating wheel side of the machine as most clearly illustrated in Figure 2. Sleeve 35 has a central bore 38 of size to just receive the larger or point end of the drill barrel so that this portion 23 of the work may be readily slipped into the sleeve when in raised position as limited by the rib 39.

Rib 39 surrounds aperture 40 designed to receive plunger 41 having a portion 42 sliding in bore 43 of block 30. This sliding movement is controlled by pin 44 riding in slot 45 and engaged in vertical slot 46 of slide block 47 which moves in the guide slot 48 of bracket 28. An actuating handle 49 is suitably pivoted as to bracket 27 and has a pin 50 engaged in block 47 for actuation thereof.

Since the fixture in question is intended for accurate positioning of the work pieces to insure proper concentric grinding thereof it is desirable that it be capable of desired vertical adjustment. To this end block 30 is connected with bracket 28 by bolts 51 engaged in the elongated slots 52 permitting of desired relative shifting of the parts while accurate positioning is assisted by employment of adjusting screw 53 carried by block 30 engaging the base portion of the bracket as shown in Figure 5. The pin and slot connection between plunger 42 and actuating block 47 permits such adjustment without in any wise disturbing the operative connection between said parts.

In the operation the sleeve 35 is swung into an upward position as shown in Figure 4 and a work piece inserted till it rests on rib 39. The sleeve is then swung downward to introduce the shank 22 thereof in the throat between grinding and regulating wheels as shown in Figure 3. As it is swung downward it is pressed against stop plate 36 bringing the fixture toward the regulating wheel and on account of the retracted position of the work there will be no engagement between work and grinding wheel during this position. In work of the type here in question the barrel of the drill is preferably formed with a cut back or relieving angle which is to say that it tapers gradually from the point toward the tapered shank but at a less degree of taper than said shank. Stop 36 is so located that at the completion of the grinding the longitudinally tapered barrel will have line contact with the work supporting sleeve at the regulating wheel side producing a clearance between guide sleeve and work as indicated at 54. Since the regulating wheel does not wear away during grinding of an individual work piece and since the sleeve is also non-wearing the two together form an absolute positioning limit for the work piece which consequently at completion of its grinding is held in the machine by means continuously engaging one side thereof, coupled with means, the ribs 21 on the work rest and 25 on the regulating wheel engaging a predetermined or selected portion of the tapered shank with the result that these two specified work position determining members insure absolute concentricity of the barrel and tapered shank portions of the work piece.

In the performance of the grinding operation after the sleeve bearing the work has been swung into proper position handle 49 is swung inwardly projecting pusher 41 through aperture 40 into engagement with the point of the drill. This action shifts the work axially into the grinding throat between grinding and regulating wheels, the tapered shank riding along rib 21 on the work rest and guided by the work control-

ling rib 25 on the regulating wheel is ground off by the action of the grinding wheel and as ground tends to recede toward the regulating wheel the fixture swinging about pivots 34 until it comes to rest against stop 36 but still being free for vertical movement to compensate for any additional rise of the work in its movement along the work rest until limited by engagement with stop 26. It will be apparent that due to the double gimbal bearing support for the fixture the same is free to follow the movement of the work in all directions except as limited by stop 36 while on account of the employment of ribs or projections 21 and 25 on the work rest and regulating wheel respectively the tapered shank being ground is also capable of limited movement to absolutely find and position itself and insure proper concentric grinding with a predetermined portion of said tapered shank employed as a determinant. This is of particular value in the event of slightly warped shanks or the like since the central position on the shank employed facilitates proper supporting of the shank during the grinding off of the terminal portions thereof in curing the warped, bent or out of round conditions thereof.

30 I claim:

1. A machine for the centerless production of concentric work piece surfaces comprising opposed grinding and regulating wheels forming a work receiving throat therebetween, a work rest projecting within the throat for supporting work pieces therein and a work supporting fixture mounted adjacent said throat and including a work holding member for engaging a terminal portion of the work and oscillatable from a work receiving position to a position to present a projecting portion of the work on the work rest in the throat between grinding and regulating wheels, and means supporting the fixture for free floating movement to permit the work to automatically adjust itself to the grinding throat.

2. A machine for the centerless production of concentric work piece surfaces comprising opposed grinding and regulating wheels forming a work receiving throat therebetween, a work rest projecting within the throat for supporting work pieces therein and a work holding member for engaging a terminal portion of the work and oscillatable from a work receiving position to a position to present a projecting portion of the work on the work rest in the throat between grinding and regulating wheels, and means supporting the fixture for free floating movement to permit the work to automatically adjust itself to the grinding throat, and means for limiting said movement in one direction when the work is

5 within the grinding throat.

3. A machine for the centerless production of concentric work piece surfaces comprising opposed grinding and regulating wheels forming a work receiving throat therebetween, a work rest projecting within the throat for supporting work pieces therein and a work holding member oscillatable from a work receiving position to a position to present a projecting portion of the work on the work rest in the throat between grinding and regulating wheels, means supporting the fixture and work for free floating movement, means for limiting said movement in one direction when the work is within the grinding throat, and means for shifting the work axially of the fixture when in grinding position.

4. A machine for the centerless production of concentric work piece surfaces comprising opposed grinding and regulating wheels forming a work receiving throat therebetween, a work rest projecting within the throat for supporting work pieces therein and a work holding member oscillatable from a work receiving position to a position to present a projecting portion of the work on the work rest in the throat between grinding and regulating wheels, means supporting the fixture and work for free floating movement, means for limiting said movement in one direction when the work is within the grinding throat, means for shifting the work axially of the fixture when in grinding position, and means for limiting said shifting movement.

5. A centerless grinder including a grinding wheel rotatable at a high grinding rate of speed and of appreciable width, an opposed regulating wheel having a narrow work engaging portion said wheel being movable at a slow rate of speed to control the position and rotation of the work piece, and a work rest sub-tending the throat between grinding and regulating wheels and having a projecting work engaging lug for engagement with the same zone on the work as is engaged by the regulating wheel whereby the position of the work piece as a whole in the grinding throat is determined by the engagement of the regulating wheel and work support with a predetermined fractional portion of said work piece.

6. A centerless grinder including opposed grinding and regulating wheels forming a work receiving throat therebetween, an oscillatable work holding fixture disposed adjacent said throat and having a portion for receiving and supporting a work piece during the grinding of a selected portion thereof, and means projectable into engagement with the supported portion of the work when the work is in grinding position for urging the work axially into the grinding throat.

7. A centerless grinder including opposed

- grinding and regulating wheels forming a work receiving throat therebetween, a work rest within the throat, a hollow work holding member exterior of the throat, a housing, a gimbal joint connecting the work holding member with the housing whereby the work holding member may be oscillated from a work receiving position to a position to present a projecting portion of the work piece within the grinding throat on the work rest blade, and means projectable from the housing into the hollow work holding member for axially moving the work piece on the work rest blade into the grinding throat. 5
8. A centerless grinder including opposed grinding and regulating wheels forming a work receiving throat therebetween, a work rest within the throat, a hollow work holding member exterior of the throat, a housing, a gimbal joint connecting the work holding member with the housing whereby the work holding member may be oscillated from a work receiving position to a position to present a projecting portion of the work piece within the grinding throat on the work rest blade, means projectable from the housing into the hollow work holding member for axially moving the work piece on the work rest blade into the grinding throat, and means limiting the axial movement of the work piece along the work rest blade. 10
9. A centerless grinder including opposed grinding and regulating wheels forming a work receiving throat therebetween, a work rest within the throat, a hollow work holding member exterior of the throat, a housing, a gimbal joint connecting the work holding member with the housing whereby the work holding member may be oscillated from a work receiving position to a position to present a projecting portion of the work piece within the grinding throat on the work rest blade, means projectable from the housing into the hollow work holding member for axially moving the work piece on the work rest blade into the grinding throat, said means comprising a pin, a slide block axially shiftable through the housing and carried by the pin, an arcuately swingable lever pivoted exteriorly on the housing, and means connecting the lever to the slide block for changing the arcuate movement of the lever to rectilinear movement of the block. 15
10. In a centerless grinder the combination of a bed, a pair of opposed grinding and regulating wheels carried thereby and forming a grinding throat therebetween, a work rest blade subtending the grinding throat and adapted to support a work piece while being operated upon by the said wheels, a bracket supporting the work rest blade and extending beyond the grinding throat, a work carrier pivotally carried by the bracket exterior of the grinding throat swingable from a position to receive unfinished pieces and have finished ones removed therefrom to a position to have a projecting portion of the work resting on the work rest blade, said work receiving member having a portion for engagement with the terminal part of the work and offering no interference to the normal floating movement of the work while being ground. 20
11. In a centerless grinder the combination of a bed, a grinding wheel rotatably supported thereby and operable at a high grinding rate of speed, an opposed regulating wheel rotatable at a relatively slow work controlling rate of speed, the wheels having their opposed surfaces spaced from one another to provide a grinding throat, a work rest blade beneath the grinding throat for supporting a work piece during the grinding operation, a block supporting the work rest blade, a work carrier, and means pivotally mounting the carrier on the block for manual movement from a position to receive a work piece to a position for inserting a portion of the work projecting from the carrier on the work rest blade within the throat and for manually reversely actuating the carrier to the work receiving position where the finished work is removed from the carrier and an unfinished one placed therein. 25
- In testimony whereof I affix my signature. 30
- CLEMENT BOOTH. 35
